UNITED STATES PATENT OFFICE.

ELISHA WILLIAM BABCOCK, OF LORAIN, OHIO, ASSIGNOR OF ONE-HALF TO JOHN E. KITCHEN, OF LORAIN, OHIO.

ARTIFICIAL LEG.

1,232,173.

Specification of Letters Patent.

Patented July 3, 1917.

Application filed July 24, 1916. Serial No. 110,830.

To all whom it may concern:

Be it known that I, ELISHA W. BABCOCK, a citizen of the United States, residing at Lorain, in the county of Lorain and State of Ohio, have invented certain new and useful Improvements in Artificial Legs, of which the following is a specification.

This invention relates to artificial limbs, and has for its main object to provide an 10 artificial foot constructed on the same general principle as that disclosed in Patent No. 1,198,399, granted to me September 12th., 1916, but simplified in design for the purpose of reducing the weight of the foot. 15 In order that the invention may be clearly understood, the same will be hereinafter fully described, reference being had to the accompanying drawings, which simply illustrate the invention, and the novel features 20 thereof will be distinctly pointed out in the appended claims.

In the drawings like characters of reference indicate corresponding parts.

Figure 1 is a side elevation of an artificial 25 foot constructed in accordance with my invention,

Fig. 2 is a sectional view taken on line 2-2 of Fig. 3, and

Fig. 3 is a plan sectional view taken on 30 line 3-3 of Fig. 2.

Referring to the drawings, 1 represents the lower portion of a leg, which may be attached to the wearer in any suitable manner. This leg may be constructed of aluminum, pressed fiber or other suitable material. Formed integrally with the leg is an upper foot member 2. The forward end of this upper foot member is reduced in width thereby leaving side spaces 3, and terminates 35 in a pair of depending circular lugs 4. A sole member 5, which is adapted to complete the lower part of the foot, terminates at its forward end in a pair of circular upturned ears 6 corresponding in size to the 40 lugs 4, against which said ears fit. A toe piece 7 is adapted to complete the forward end of the foot, and its thickened sides 8 fit against the ears 6. The ears 6 of the sole member and the sides 8 of the toe piece entirely 45 fill the spaces 3, and these parts are pivotally connected to the lugs 4 of the upper foot member by means of a pin 9. A suitable flat spring 10, fixed to the toe piece at 11 and having its other end engage the 50 sole member 5, tends to keep the toe piece

in normal position. Cushion bumpers, such as 12, project from the sole member at the joint, to prevent the edge 13 of the toe piece making a noise by striking the opposite edge of the sole member.

The weight of the wearer is resiliently supported upon a suitable coiled spring 14, which is arranged between the heel 15 of the sole member 5 and a bar 16 extending from the forward to the rear wall of the leg. In 60 order to provide convenient means for placing said coiled spring in position, and also to provide means for readily adjusting the tension thereof to suit the weight of the wearer, the following construction is employed. The heel of the sole member is provided with an opening 17, from which projects an internally threaded boss 18 for receiving a tubular plug 19. Said coiled spring rests within this tubular plug, and 65 its upper end is held in alignment therewith by means of a centering boss 20 depending from the before mentioned bar 16. Said tubular plug is screwed into or out of the internally threaded boss 18 by the use of 70 any suitable tool which may be inserted in the square hole 21.

The movement of the upper foot member 2 with relation to the sole member 5, during the walking action, is limited by means 85 of a nib or stop 22, which projects inwardly from the raised portion 23 of the sole member and slides in a groove 24 formed in the rear wall of the upper foot member. This part being cut back at 25 for accommodating the raised portion 23 of the sole member. A flange 26, at the lower end of said groove, is adapted to engage the stop 22, when the wearer is taking a step, and thus limit the movement of the upper foot member with 90 relation to the sole member. A cushion of suitable material may be provided at 27 for deadening the sound.

It is thought that the action of this foot will be understood and its advantages appreciated without further explanation.

Having fully described my invention, what I claim is:

1. In an artificial limb, the combination of a leg portion having an upper foot member, the upper foot member having depending lugs at its forward end, a sole member, the sole member having upturned ears at one end, a toe piece, the toe piece being pivotally connected to said ears and said lugs, a spring for keep- 105

ing the toe piece in normal position, cushion bumpers projecting from the sole member adapted to prevent the toe piece striking said sole member when returning to normal position, and means for resiliently supporting the free end of the upper foot member from the sole member, substantially as described.

2. In an artificial limb, the combination 10 of an upper foot member, a sole member, the sole member being pivotally connected to the forward end of the upper foot member,

means for resiliently supporting the free end of the upper foot member from the outer foot member, the rear end of the upper foot member having a groove, a stop projecting from the sole member into said groove, and the upper foot member having a flange at the end of said groove adapted to engage said stop limiting the movement of the upper foot member with relation to the sole member, substantially as described.

15 In testimony whereof I affix my signature.

ELISHA WILLIAM BACCOCK.
